UNITED STATES PATENT OFFICE.

ROBERT A. REGESTER, OF BALTIMORE, MARYLAND.

BOILER-TUBE CLEANER.

SPECIFICATION forming part of Letters Patent No. 334,468, dated January 19, 1886.

Application filed April 7, 1885. Serial No. 161,447. (No model.)

To all whom it may concern:

Be it known that I, ROBERT A. REGESTER, a citizen of the United States, residing at Baltimore, in the State of Maryland, have invented certain new and useful Improvements 5 in Boiler-Tube Cleaners, of which the following is a specification, reference being had to the accompanying drawings.

My invention relates to improvements in boiler-tube cleaners in which the cleansing is effected by the action of steam, and it is so arranged that a cut-off valve is operated automatically, and constructed in such a manner that the steam is ejected through a cylindrical 15 cone-shaped passage, which directs the same against the interior of the tube, as illustrated in the accompanying drawings, in which—

Figure 1 is a vertical section through the entire device, showing the cut-off valve open; 20 Fig. 2, a like section view of the device, showing the cut-off valve closed; Fig. 3, a cross-section on line *x*, and Fig. 4 a detail view of the interior shell.

Similar letters refer to similar parts throughout the several views.

The letter *A* designates the body of the casing, which is made in the form of a cone, so that it may be used in tubes of various diameters without any adjusting, and which comes 30 in contact with the end of the tube, thereby closing the same and preventing any back escape of the refuse. To the apex of this cone is arranged a flaring neck, *b*, in which is placed a center piece, *a*, the angles of which 35 correspond to those of the neck *b*, thus forming a cylindrical cone-shaped passage, *m*, by which the steam, as it passes through the same, is directed outward against the interior surface of the tube. The center piece, *a*, is held in 40 its position by the stem *a'*, which is secured to a cross-arm, *c*, by the nuts *c'* and *c''*, the latter being threaded on the stem *a'*, and the arm *c* rigidly secured to or cast integral with the casing *A*, the whole securing the said center 45 piece, *a*, firmly to the casing.

From the base of the body-piece *A* projects a second neck, *d*, provided with an annular projection, *d'*, to which is secured a suitable packing-ring, *e*, the said neck being bored out, 50 and in which is placed the annular shell *B*, the exterior of which is turned to form a neat

fitting joint between it and the neck, by which one may slide on the other and make as near as possible a steam-tight joint. The shell *B* is provided with the thread *f*, by which it is 55 attached to the steam-pipe; the bearing *g*, through which the stem *a'* passes, and by which the shell and stem are held in their proper relation to each other; an annular seat, *h*, which comes in contact with the packing-ring *e*, and 60 thereby forms a steam-tight joint at that part when not using the device, as shown in Fig. 1; the slots *i*, which prevent the shell from turning by coming in contact with the cross-arm *c*, and a packing-ring, *k*, which comes in 65 contact with the seat of the valve *l*, and thereby preventing the escape of the steam while the device is being removed from one tube to another, the valve *l* being secured to the stem *a'*, and thereby rigidly attached to the body *A*. 70

The operation is as follows: The device is secured to the steam-pipe, which is connected to the boiler in the usual manner, and the parts of the device are then in position to each other as shown in Fig. 2, with the valve *l* seated on 75 the packing-ring *k*, which prevents the steam from escaping. The device is then inserted in a tube of the boiler until the body portion *A* comes in contact with the end of the said tube, which prevents that portion from moving any farther forward; but, as the pressure is still applied to the steam-pipe by the operator, the movement of the shell *B* is continued 80 inward, which unseats the valve *l*, and thus permits the steam to pass into and from the 85 passage *m*, which effectually removes the deposit from the tube. When the tube has been sufficiently blown or cleansed, the operator releases the inward pressure he has maintained to hold the device in its place, which permits 90 the steam-pressure to act on the valve *l*, thus closing the same and preventing any farther passage of the steam until the device is again placed in another tube and the force or pressure applied to the same by the operator, and 95 so on, thus affording a device that is simple in its construction and operation, not liable to get out of order, and which may be conveniently and quickly operated.

Having fully described my invention, what 100 I claim, and wish to secure by United States Letters Patent, is—

1. In a boiler-tube cleaner, the combination of the body-piece A, provided with the cross-arm c, and the sliding shell B, provided with the slots i, that engage with the cross-arm c, whereby the shell is prevented from turning.

2. In a boiler-tube cleaner, the combination of the body part A, formed cone-shaped to fit different size tubes, the flaring neck b, secured to the apex of the cone A, the central part, a, formed with like angles to the neck b, by which the cylindrical cone-shaped passage m is formed, the stem a', arranged to support the center part, a, the cross-arm c, secured to the casing A, the shoulder or nut c', and the nut c", by which the stem a' is securely held to the arm c, thus centrally supporting the part a, by which the passage m is free from any obstruction.

3. In a boiler-tube cleaner, the combination of the cone-shaped body A, the flared neck b, the center part, a, by which the cylindrical cone-shaped passage m is formed, the neck d, the shell B sliding therein, the packing-ring e, interposed between suitable seats on the neck d, and the shell B, by which the steam is prevented from escaping when the device is operating, and the cut-off valve l, by which the steam is cut off when the device is not in operation, as herein specified.

In testimony whereof I affix my signature in presence of two witnesses.

ROBERT A. REGESTER.
